UNITED STATES PATENT OFFICE.

JOHN WILLIAM WHITE, OF BUFFALO, NEW YORK.

DISK WHEEL.

Application filed December 28, 1922. Serial No. 609,497.

To all whom it may concern:

Be it known that I, JOHN WILLIAM WHITE, a citizen of the United States, residing at 122 Bedford Avenue, Buffalo, in 5 the county of Erie and State of New York, have invented certain new and useful Improvements in Disk Wheels, of which the following, taken in connection with the accompanying drawings, is a specification.

10 This invention relates to an improvement in disk wheels and more particularly to the formation of the disk and the means by which it is secured to the wheel rim.

Disk wheels are of two general types; 15 first, those in which the rim is detachably mounted upon the disk and second, those in which the rim is permanently secured to the disk by means of rivets or welds.

This invention relates to disk wheels of 20 the first type and its chief object is to provide means for demountably connecting the rim to the disk which means permit a certain relative rocking of the rim and the disk and at the same time positively insure 25 the correct location of the rim on the disk.

A further object is to provide a disk wheel 30 in which the disk has, adjacent the rim, an annular band, the face of which band lies in a plane at right angles to the wheel axis behind the line of the center of the wheel so that the valve stem, through which, under ordinary conditions, the center line 35 of the wheel passes, lies entirely in front of the disk and so that no radial depression or other deformation of the disk band is necessary in order to accommodate the valve.

Other objects will appear from the details 40 of construction set forth in the following specification and in the accompanying drawing which forms a part thereof and in which—

Figure 1 is a front elevation of a disk 45 wheel embodying one form of this invention;

Figure 2 is a similar view of the disk itself;

Figure 3 is a cross section taken through 50 the line 3—3 of Fig. 2;

Fig. 4 is an enlarged cross section taken along the line 4—4 of Fig. 1;

Fig. 5 is a similar enlarged cross section taken along the line 5—5 of Fig. 1;

55 Fig. 6 is an enlarged cross section taken along the line 6—6 of Fig. 1; and

Fig. 7 is a section taken along the line 7—7 of Fig. 6.

In order to facilitate the description certain terms are used in the specification and claims with respect to which arbitrary meanings have been applied. Thus the term "under side" has been used in connection with the rim to denote the face of the rim nearest the axle in other words that portion of the rim with which the disk engages. The terms "upper" "lower" "below" are used with reference to the hub regardless of the actual relative positions that the parts so designated assume as the wheel is 70 rotated. Hence a part nearer the hub than another part is described as being "below" or "lower" than the other.

Referring to the drawing it will be noticed that the disk wheel comprises a disk 75 10 and a rim 11. The rim 11 is demountably secured to the disk 10 by means of a locking ring 12 and a plurality of bolts 13 which project from the periphery of the disk and are engaged by nuts 14. When 80 assembled these parts, of course, function as a single unit and are intended to be mounted upon a wheel hub (not shown) of suitable construction. This is a common construction and since no novelty is claimed 85 therein, it is believed there is no necessity of illustrating it.

Formed on the under side of the rim 11 is an annular bead 15 the outer face 16 of which is perpendicular to the base of 90 the rim 11 and the inner face 17 of which is inclined to the rim at approximately thirty (30) degrees. This bead 15 is located on the inner half of the rim 11 and is so positioned that the outer face 16 lies 95 in a plane parallel to and a specified distance behind the center plane 18 of the wheel.

The disk 10 is formed adjacent the rim 11, with an annular band 19 which lies in the 100 same plane as the face 16. At the outer edge of the disk is a flange 20 suitably inclined so that when the disk and rim are assembled the flange 20 will contact with the face 17 of the bead 15. The locking ring 105 12 is of channeled cross section having an upper leg 21 and a lower leg 22 both legs being of the same depths, and when assembled the upper leg 21 bears against the face 16 of the bead 15 while the lower 110 leg 22 bears against the band 19 of the disk 10. When the nuts 14 are tightened on

the bolts 13, it is obvious that the pressure of the ring 12 will seat the rim 15 upon the flange 20 in the proper position, with the face 16 of the bead in the plane of the band 19 of the disk. Thus, by the construction above set forth the proper location of the rim upon the disk is insured under all conditions. The advantages of such a construction are believed to be obvious and need not be pointed out in detail.

Through the base of the rim 11 is provided a hole 23 through which the valve stem 24 of the pneumatic tire (not shown) of the wheel will extend. The center plane 18 of the wheel passes through the center of the hole 23 so that the valve stem lies in the center plane. The legs 21 and 22 of the ring 12 are cut away at 25 and 26 and when the parts are assembled the valve stem 24 will be located in these cut away portions 25, 26.

In order to secure the tire firmly to the rim, it is the usual custom to employ a locking nut 27 which is threaded upon the valve stem 24 and which, in a wooden wheel for example, bears against the under side of the felloe. In place of the felloe of a wooden wheel and to insure the proper rigidity of the valve stem 24, the disk band 19 is cut and depressed at 28 to provide a pocket 29. The distance of the edge 30 from the rim is the same as the width of the locking ring 12 and thus the nut 27 will bear against the edge 30 of the band 19 and also against the legs 22 of the ring 12.

The pocket 29 in the disk also permits the application of an air tube to the end of the valve stem without in any way scarring the surface of the disk. Furthermore, this depression permits the application of the valve cap 31 so that the same valve stem can be used in this particular type of disk wheel here shown as in a wooden wheel. Thus it is possible to employ any type of valve in connection with this disk wheel and moreover, it is not necessary to change in particular the valve stem construction.

The particular type of rim shown is of the straight side split ring variety the sections 32, 33 being joined at the split 34 by a lug 35 which is carried by the section 32 and which enters a slot in the section 33. This lug 35 has a tapered face 36 which as indicated on Fig. 6 coincides with the tapered face 17 of the bead 15 and terminates at the inner edge of the bead. The flange 20 thus seats against the lug as well as against the bead.

In order to prevent any relative rotation between the disk and the rim a notch 37 is provided in the leg 21 of the lock ring 12 the sides of which engage the sides of the lug 35. Thus all power is transmitted between the disk and the rim by the lug 35 ring 12 and bolts 13 and any deformation of the flange 20 of the disk is avoided.

While one embodiment of this invention has been shown and described, I am not to be limited thereto since it is obvious that others may be made without departing from the spirit and scope of the invention as set forth in the following claims.

Having thus set forth my invention what I claim as new and for which I desire the protection of Letters Patent is:

1. In a disk wheel, a disk having an annular band in a plane parallel to and behind the center plane of the wheel, and an inclined flange at the outer edge, a demountable rim, a bead on the underside of said rim, the outer face of said bead being perpendicular to the base of said rim in the plane of said annular band, and the inner face of said bead being inclined to said base, whereby, when the wheel is assembled, the inner face of the bead rests upon the inclined flange of the disk, and a clamping ring having upper and lower legs of the same depth for securing said rim in position upon said disk, the upper leg of said ring bearing against the outer face of said bead and the lower leg bearing against said annular band.

2. In a disk wheel, a rim, a disk having a continuous annular band adjacent said rim, and in a plane parallel to the center plane of the wheel, a bead on the underside of said rim, one face of which bead is perpendicular to the base of said rim and lies in the same plane as the band on said disk, the plane of said band and bead being so located with reference to the center plane of the wheel that the valve stem of a tire on said rim, which stem is in the center plane of the wheel, projects from said rim in front of and out of contact with said bead and band and a clamping ring for securing said rim to said disk, said ring comprising upper and lower legs, the inner leg bearing against said annular band and the upper leg bearing against the perpendicular face of said bead and notches through said upper and lower legs for the valve stem.

3. In a disk wheel, a split rim, a lug on the underside of said rim for holding the sections of the rim in functioning position, a bead on the underside of said rim terminating at said lug, a disk having a flange with which said bead engages, clamping means for holding said rim to said disk, and means for securing said clamping means to said disk, said clamping means also engaging said lug and preventing relative rotation between said disk and said rim.

4. In a disk wheel, a rim, a disk having adjacent the rim an annular band in a plane parallel to the center plane of the wheel, a valve hole in said rim in the center plane of the wheel through which hole the valve stem of a pneumatic tire on said rim projects, the band of said disk being so lo-

cated behind the center plane of the wheel that the valve stem is in front of and out of contact with said band, a clamping ring for securing said rim to said disk, and having
5 a notch in which the valve stem lies, and a pocket in said disk below said band the upper edge of said pocket being the same distance from the rim as the lower edge of said clamping ring whereby the lock nut on
10 the valve stem seats against the underside of said ring and the edge of said pocket.

5. The combination with a wheel having an inwardly inclined peripheral portion of

a demountable rim having an annular bead on its underside behind the median plane 15 of said rim, the outer face of said bead being perpendicular to said rim and in a plane parallel to said median plane, and the inner face of said bead being inwardly inclined to rest upon the inclined peripheral portion 20 of said wheel and clamping means engaging the outer face of said rim bead and said wheel.

In testimony whereof I have affixed my signature.

JOHN WILLIAM WHITE.
